GARMENT HANGER

Karl R. Tromp, Chicago, Ill.

Application April 18, 1935, Serial No. 16,951

7 Claims. (Cl. 223—93)

This invention relates to a garment hanger, and more particularly to a hanger provided with clamping arms for securely holding a dress or other garment in position thereon.

5 One of the main objects of this invention is to provide an improved garment hanger having clamping arms which can be easily and positively moved into the open position and likewise into the closed position by a single and slight pressure of the fingers, and which will be held securely in either of such positions until it is again actuated and moved into the opposite position.

10 Another object is to provide such a hanger wherein only a single operating member is required, with which both clamping arms are moved positively into either the open or the closed position and whereby they are firmly held in such position; thus providing a simple and inexpensive device which can be readily operated by engaging and moving said single operating member.

15 These and various other objects and advantages are attained with this invention as will become apparent from the following description taken in connection with the accompanying drawing wherein this invention is shown in its preferred form, it being understood that various other arrangements and forms of construction may be resorted to for carrying out the objects and purposes of this invention.

20 In the drawing:

Fig. 1 is an elevational view showing a garment hanger embodying my invention in its preferred form of construction, showing the clamping arms in the closed position.

25 Fig. 2 is an elevational view of this invention, showing the arms and operating means in the open position.

Fig. 3 is a fragmentary vertical sectional view through the device.

30 Fig. 4 is a substantially horizontal sectional view, taken on lines 4—4 of Fig. 3.

Figs. 5 and 6 are cross-sectional views, taken respectively on lines 5—5 and 6—6 of Fig. 3.

35 In the drawing I have illustrated my invention in its preferred form of construction, comprising a pair of clamping arms 10 which are oppositely disposed upon a supporting bar 11, the bar being provided with the usual supporting hook 12 at its middle portion.

40 For the sake of economy, each arm is preferably made of a strip of sheet metal, which is arched or curved to conform to the rounded top face of the bar, and also has its outer end 10' turned upwardly, as indicated in the drawing. A collar 14 is provided on the inner end of the arm, being

preferably integral therewith and formed from depending strips 14' on the arm which are secured together at the bottom. Said collar surrounds the bar 11 and permits vertical swinging of the arm thereon.

5 The means for operating the pair of arms is preferably in the form of a flexible member or strip 15, which consists of a leaf spring. Adjacent its two end portions the spring is firmly secured to the bottom parts 14' on the two collars, 10 so that by moving or flexing of this member 15 the pair of clamping arms 10 are positively moved or swung into the open position and into the closed position.

10 Means is provided for retaining the spring and 15 the arms in position on the bar, and this means is preferably in the form of a pair of abutment members 17, which, for the sake of economy, are provided in the shape of thin sheet metal yokes which are secured on the bar by means of rivets 20 18, so that the lower or bight part 17' of the yoke remains seated against the lower face of the bar. A curled flange or lip 19 is provided on the inward edge of said bight part, preferably by forming a projecting flange or lip thereon which is rolled 25 upwardly, as indicated in the drawing.

15 The two ends 20 of the spring or operating member 15 are bent slightly upwardly, and the curled lip 19 of each abutment member 17 rests in the groove or channel formed between the 30 bent-up end 20 and the lower end portion 14' of collar 14, as best shown in Fig. 3. With this arrangement the two bent-up ends 20 of the spring ride or bear slidably upon the two curled lips 19 on yokes 17, so that the spring is normally 35 retained arched or bowed and under tension, as best shown in Figs. 1 and 2, and whenever the spring is being operated these bent ends 20 yield and deflect, due to their pressure against the curled lips 19, and permit the spring to straighten 40 and change from one position to the other. A covering 21 of soft or pliable material is preferably also placed around the spring.

45 With this arrangement the spring is normally held bowed and flexed and therefore retained 45 firmly in position, thereby also firmly holding the pair of arms in either the closed position as shown in Fig. 1, or in the open position as shown in Fig. 2. The device is readily operated by a slight upward pressure of the fingers upon the 50 operating spring 15 to move it and the arms from the open position to the closed position; and likewise, by a slight finger pressure the spring can be drawn downward to move it and the arms from the closed position to the open position. 55

This arrangement and construction includes a minimum of parts thereby providing an inexpensive device, and is very easily operated by a slight pressure of the fingers. The arms are also positively moved by the movement of the operating spring, and they are furthermore held firmly in the closed position to hold the garment upon the bar, and are similarly held firmly in the open position so that a garment can be readily placed thereon.

10 I claim:

1. A garment hanger comprising a supporting bar, a pair of clamping arms and means associated therewith for movably mounting them upon said bar, an oblong flexible member which has its end portions connected with said means, and abutment means on the bar engaging the end parts of said member to hold it flexed in either the open position or in the closed position, so as to move said arms positively into either the open position or the closed position by the flexing of said member, through an application of force in a single direction, and to hold the arms firmly in position.

2. A garment hanger comprising a supporting bar, a pair of clamping arms upon said bar each having means thereon extending downward along the bar for mounting the arms movably thereupon, an operating member beneath the bar having its end portions firmly secured to said means for moving them together, and means on the bar for retaining said member and arms securely in either the open position or in the closed position thereon, whereby to positively move both of said arms into either one of said positions by the application of force in a single direction.

3. A garment hanger comprising a supporting bar, a pair of clamping arms upon said bar each having a collar fixed thereon surrounding the bar for mounting the arms movably thereon, a flexible strip having its end portions secured to said collars, and abutment means on said bar engaged by said collars and said strip, whereby the arms and collars are movable along with the movement of said flexible member into their open position and into their closed position by a slight pressure of the fingers upon said member.

4. A garment hanger comprising a supporting bar, a pair of clamping arms positioned upon

said bar each having a collar thereon surrounding the bar, a flexible strip adjacent the ends of which said collars are secured so that the collars and arms are positively moved therewith and held thereby in either the open position or the closed position, and abutment means on said bar which the ends of said strip removably engage to keep the strip flexed and hold the arms firmly in either the open position or the closed position but to enable convenient operation thereof.

5. A garment hanger comprising a supporting bar, a pair of clamping arms upon said bar, a leaf spring having bent ends, means for securing the pair of arms to the spring adjacent said ends so that the arms move along therewith into the open position and into the closed position, and means on the bar including curled lips against which the ends of the spring slidably bear, to retain it bowed and under stress and thereby hold said arms in position, said ends being slidable on said curled lips to enable convenient operating of the spring and thereby the arms by a slight pressure of the fingers.

6. A garment hanger comprising a supporting bar, a pair of arms upon said bar, each having an integral collar thereon surrounding the bar, a leaf spring having bent-up ends, said collars being secured to the spring adjacent said ends, and thin sheet metal means secured on said bar including curled lips against which the bent ends of said spring bear flexibly, thereby retaining the spring bowed and under stress to firmly hold the arms in either the open position or the closed position, and to enable easy operation thereof.

7. A garment hanger comprising a supporting bar, a pair of arms upon said bar, each arm having an integral collar movably surrounding the bar, a flexible member having bent elements at the two opposite ends, the pair of collars being secured to the member adjacent said ends to move the arms thereby to the open position and to the closed position, and abutment means on said bar including lips against which said bent elements bear, thereby retaining said member flexed and stressed to firmly hold the arms in either the open position or in the closed position, to enable operating the same by a slight finger pressure.

KARL R. TROMP.
